UNITED STATES PATENT OFFICE.

ALBERT GRIEVES, OF SPRINGFIELD, OHIO, ASSIGNOR TO INTERNATIONAL HAR-
VESTER COMPANY, A CORPORATION OF NEW JERSEY.

BLOCK-SETTING MECHANISM FOR BALING PRESSES.

Application filed June 23, 1919. Serial No. 305,993.

To all whom it may concern:

Be it known that I, ALBERT GRIEVES, a citizen of the United States, residing at Springfield, in the county of Clark and State 5 of Ohio, have invented certain new and useful Improvements in Block-Setting Mechanism for Baling Presses, of which the following is a full, clear, and exact specification.

10 This invention relates to baling presses, and more particularly to block setting mechanism for baling presses.

In presses employed for baling hay and like material, it is customary to interpose 15 blocks between the adjacent bales, the blocks having cutaway portions adapted to receive the baling wire with which the bale is bound. If the press is to be efficient and successful in operation, it is necessary that the 20 blocks be placed in position in the block setting mechanism, and be transferred from the block setter to the baling chamber of the press easily and expeditiously.

The present invention has for its object, 25 therefore, to provide a construction of setter in which a block may be easily, quickly and accurately positioned and from which the block may be discharged by any suitable means when desired.

30 In carrying out the objects above noted, I have in the present instance provided a manually operable block setter, the setter having means for retaining the block in position, this retaining means being operable 35 to release the block when the block is engaged by a moving member carried in this instance by the feeder head. The block retaining member may be normally maintained in a position to limit the movement 40 of the block, by resilient means, and in the particular construction illustrated, means has been provided for co-operating with this block retaining member when the block setter is in its normal or inoperative position 45 to limit the outward movement of the retaining member, thereby limiting the position into which the block may be forced by the operator of the machine.

In the embodiment of the invention illus- 50 trated in the drawings,

Fig. 1 shows in side elevation a portion of a baling press, having my improved block setter thereon;

Fig. 2 is a top plan view of the block set- 55 ter shown in Fig. 1;

Fig. 3 is a vertical sectional view of the improved block setter;

Fig. 4 is a rear elevational view, partly in section, illustrating the block setter in the position it assumes when the block is to be 60 discharged therefrom; and

Figs. 5 and 6 are detail views showing the construction of the block retaining member, Fig. 5 being the side elevational view and Fig. 6 being a top plan view of this member. 65

The baling press, in connection with which my invention is illustrated, is the ordinary plunger type of press, having upper and lower side frame members 10 and 11, and having side members 12 (one of 70 which is illustrated) for enclosing the baling chamber. A feeder head 13 is provided for feeding the hay into the baling chamber, this head being actuated by feeder arms 14 connected in any suitable manner to the 75 driving mechanism. The head 13, as illustrated, is provided with a resilient outwardly projecting member 15, adapted to engage the block when the block setter has been moved to operative or block setting position 80 and to force the block into the baling chamber. Any other form of block discharging mechanism may be used if desired, the form illustrated being merely shown for the purpose of disclosing a complete operative 85 structure, including one form of block discharging means.

As stated above, the form of block setter illustrated in connection with my invention is a manually operable type, the setter being 90 pivoted to a frame in a manner described below.

A pair of bracket members 16, substantially triangular in outline, is secured by any suitable means to the said frame members 10 of the baling press. These bracket members form the support for the block setter, and also serve as guides for the block setter as the setter is swung about its pivot. As illustrated more particularly in 100 Fig. 3, the brackets 16 are provided at their upper ends with inwardly projecting flanges 17, forming, with offset portions 18 of the brackets, channels for the reception of lugs carried by the block retaining members, as 105 hereinafter described. The block setter comprises a pair of L-shaped brackets 19 pivoted at 20 to the brackets 16, and each supporting on its upper surface an angle iron or receiving member 21, these members 110

receiving the block 22, as illustrated in Figs. 1, 2 and 4. The members 21 are connected together and braced by means of transverse members 23 and 24, the member 24 being extended beyond the outer surfaces of the members 21, and being provided with apertures 25. A pair of arms 26 is secured to the rear ends of the members 21, and these arms form a support for the block setter, 10 when the setter is in its normal position, by the engagement of the lower ends of its arms with the upper surfaces of the side frame members 10 of the press. As illustrated in Fig. 1, the arms are extended 15 above the block setter to form handles 27, by means of which the setter may be manually swung on its pivots 20 to a block setting position. In connection with my improved 20 block setter, I have provided resilient means for retaining the block in position in the setter, this means comprising a pair of substantially flat metallic strips 28, having journal brackets 29 secured at their rear ends. The brackets 29 are pivoted on pins 25 30 carried by the members 26, as clearly illustrated in Fig. 1. These brackets also are provided with recesses 31 for the reception of a laterally extending upper end portion 32 of a pair of clips 33, which extend 30 downwardly, passing through the apertures 25 in the member 24. The clips 33 are provided at their lower ends with nuts 34, and intermediate the nuts 34 and the lower surface of the outwardly extending 35 portions of the transverse member 24 there are provided spiral compression springs 35. As illustrated in Fig. 1, these springs exert a downward force on the clips 33, thereby forcing the member 28 downwardly into 40 engagement with the upper surface of the block 22. The members 28 are provided on their free ends with downwardly extending or off-set portions 36 which limit the inward movement of the block 22, and these 45 members are also provided with laterally extending lugs 37 which in the normal position of the block setter project into the channels formed by the portions 17 and 18 of the brackets 16. From the above description 50 it will be seen that the portion 17 of the brackets normally limit the upward movement of the members 28, thereby retaining these members in operative position of the block setter in the position shown 55 in Fig. 1. Since these members are retained in this position, the inward movement of the block 22 is limited, and the block is prevented from extending through the block setter. It will be readily seen that without 60 some means for limiting the outward movement of the members 28, a careless operator might by exerting too great an amount of force in inserting the block in the setter 65 force the block entirely through the setter and into the baling chamber, thereby caus-

ing injury to the machine and possibly serious damage to the feeder head. Means has also been provided on the brackets 19 for limiting the movement of these brackets about their pivots 20, this means comprising laterally projecting lugs 38 which engage the rear edges 39 of the brackets 16 as the block setter is swung to the dotted line position shown in Fig. 1.

It is believed that the operation of the device above described will be clear, but a brief statement of the operation will be given. When the block setter is in a normal or inoperative position, shown in full lines in Fig. 1, a block may be inserted by merely placing the block in the rear end of the setter in the block supporting members 21, and forcing the block into the setter as far as possible. The block will then be located in its proper position, and since the lugs 37 are in engagement with the channels in the brackets 16, the outward movement of the members 28 is limited and therefore the offset ends 36 definitely limit the inward movement of the block. The operator therefore need exercise no special care in inserting the block. When a sufficient amount of material has been fed into the baling chamber to form a bale, the block setter is swung to the position shown in dotted lines in Fig. 1, and during this operation the lugs 37 pass out of the channels in the brackets 16, thereby releasing the members 28 for movement about their pivots when the block is engaged by the member 15 carried by the feeder head. It will be understood that the springs 35 are of sufficient strength to retain the members 28 in the normal position shown in Fig. 1, in which position the block is held in the block 105 setter until the block is forced downwardly by means of the engagement of the block by the feeder head.

From the above specification setting forth the construction and operation of my improved block setter, it will be seen that I have provided a simple and effective construction, a construction adapted to receive the block and to retain it in position without the exercise of undue care by the operator, and also adapted to release the block when the setter has been swung to a position in which the block may be engaged by the block discharging member.

While I have in the above specification described one embodiment of my invention, it should be understood that the invention is capable of modification, and that modifications and changes may be made without departing from the spirit and scope of the 125 invention, as expressed by the following claims.

I claim—

1. In a baling press, a frame, a block setter pivotally mounted thereon, resilient

means carried by the block setter for yieldingly retaining a block in the setter when in discharging position, and means engaging the resilient means when the setter is in block receiving position to positively limit insertion of a block.

2. In a baling press, a frame, a block setter carried thereby, and having resiliently mounted block retaining means thereon, and means for limiting the outward movement of said retaining means.

3. In a baling press, a frame, a block setter carried thereby and having resiliently mounted block retaining means thereon, and means carried by said frame for limiting the outward movement of said retaining means.

4. In a baling press, a frame, block setting mechanism pivoted thereto, block retaining means carried by said block setting mechanism, and means engaging said block retaining mechanism when said mechanism is in its normal inoperative position for limiting the movement of said retaining mechanism.

5. In a baling press, a frame, block setting mechanism pivoted thereto, resiliently actuated block retaining means carried by said block setter, and means carried by said frame and engaging said block retaining means when said block setting mechanism is disposed in its inoperative position for limiting the outward movement of said retaining means.

6. A block setter for baling presses, including in combination block supporting members, and resilient means cooperating with said supporting members for retaining a block in engagement therewith.

7. In a baling press, a frame, a block set-

ter having a pair of forwardly extending brackets pivoted to the frame, means carried by said block setter for supporting the rear end of the setter on said frame, and manually operable means carried by said last named means whereby said block setter may be swung on its pivot to operative position.

8. In a baling press, a frame, supporting brackets carried thereby, block setting mechanism pivoted to said supporting brackets, block retaining means carried by said block setting mechanism, and means carried by said supporting brackets and engaging said retaining means for limiting the outward movement of said retaining means.

9. In a baling press, a frame, a pair of brackets pivoted thereto, an L-shaped receiving member secured to each bracket, transverse members connecting the receiving members, supporting members connected to the receiving members and adapted to engage the frame, retaining means pivoted to the supporting members, and resilient means engaging the retaining means and one of the transverse members.

10. In a baling press, a frame, a pair of L-shaped brackets pivoted thereto at one end, receiving members secured to the opposite ends of the brackets, transverse members connecting the receiving members, supporting members secured to the receiving members and adapted to engage the frame, and means connected to the supporting members for retaining the block on the receiving members.

In testimony whereof I affix my signature.

ALBERT GRIEVES.
